UNITED STATES PATENT OFFICE.

PALMER J. JONES, OF PORT WASHINGTON, NEW YORK.

DESK AND SEAT CONSTRUCTION.

1,402,501.

Specification of Letters Patent.

Patented Jan. 3, 1922.

Application filed May 5, 1920. Serial No. 379,016.

To all whom it may concern:

Be it known that I, PALMER J. JONES, a citizen of the United States of America, residing at Port Washington, New York, 5 have invented new and useful Desk and Seat Constructions, of which the following is a specification.

My invention relates particularly to apparatus for school use, and the main object 10 is to provide a simple and inexpensive construction which is sanitary and durable and which can be easily adjusted.

Another object is to provide a construction from which either the desk or seat 15 may be removed so that the remainder may be used separately.

Another object is to provide a construction in which the desk and seat are adjustable in height.

20 In its preferred form, a post or standard is provided with a suitable base, side flanges for supporting the seat and desk and one or more webs for re-enforcing the standard and affording means for positioning the 25 seat. Preferably the standard is inclined somewhat so that when the seat is raised it is also drawn backward. The desk also is preferably vertically adjustable being clamped to the standard by bolts slideable 30 in vertical slots.

Fig. 1 is a side view of a construction embodying my invention showing the upper end of the standard and a part of the desk in section.

35 Fig. 2 is a horizontal section of the seat support on the plane of the line 2—2 of Fig. 1.

Fig. 3 is a perspective view of the post or standard.

40 Fig. 4 is a perspective view of the seat support or bracket.

The standard and its base may conveniently be formed of cast iron or steel and is provided with a base 6, which is rectangular in outline so as to provide a maximum support, and it may be cut away at the sides to make it lighter in weight. The body 7 of the standard supports the seat 8 and the desk 9. Preferably re-enforcing 45 webs 10 and 11 are provided, one of which extends substantially to the upper end of the post or standard so as to re-enforce it and afford positioning means for the seat. In this case, the web 11 is slotted at 50 to allow vertical adjustment of the clamping bolt 13.

The support 14 for the seat is in the form of a split ring having extension jaws 15 for gripping the edges of the support as shown in Fig. 2. The support may be 60 formed of cast iron or steel which is more or less resilient so as to permit the jaws 15 and the sides 16 to be clamped against the standard and the web 11 by means of the bolt 13. To facilitate attachment and 65 detachment of the support, the standard may be cut away at 17 to a width somewhat less than the normal spacing of the jaws 15. It will be obvious therefore that the seat and its support may be readily removed 70 from the standard by simply withdrawing the bolt 13 and raising the support until the jaws 15 are disengaged from the sides of the support 7 at 17. It will be seen that this in no way disturbs or affects the desk 9. 75

The desk is secured in place by a plurality of bolts such as 18 which pass through slots such as 19 and 20 in the standard. Preferably the upper end of the standard is somewhat wider than the lower part to 80 give a better bearing surface. To re-enforce the desk where these bolts pass through, I preferably provide a bar or plate or plates such as 21, through which a plurality of bolts extend. These bars or plates are preferably of metal so as to tie a plurality of bolts together and distribute the strain so that a maximum strength may be provided with a minimum amount of material. The desk may be adjusted up and down by loosening the bolts 18 and moving the desk to the desired height, and then tightening the bolts. By having the nuts on the bolts inside the desk, they are out of the way and out of sight, and less likely to be loosened 90 accidentally or intentionally by children. 95

It will be obvious that the seat and its support may be omitted from the front row of desks if desired, and similarly, that the desk part may be omitted from the rear 100 row of seats. It will also be obvious that the upper end of the post or standard may be omitted or the standard cut off at the point 22 in case the desk is not needed. In this way adjustable seats may be provided 105 for the rear row of seats to match the other desks and seats of a given set.

To support the standard, I prefer to provide a plurality of clamps such as 23, each having a foot portion adapted to be secured to the floor by a screw or bolt 24, and another portion to overlap the edge of the 110

base. This will permit the base to be secured to the floor at any position irrespective of knots or cracks in the floor which make it very difficult to attach the ordinary base to the floor by screws which pass through definitely located holes in the base.

By inclining the standard slightly to the rear I find that a better distribution of the weight on the seat is provided.

10 I claim:

1. A seat construction, comprising a base, a single post rising centrally therefrom and having laterally projecting flanges and a web between said flanges and connecting the base with said flanges, a seat support embracing said web and said flanges, and means for adjustably clamping said support against said flanges and said web.

2. A combined seat and desk construction, comprising a base, a single standard rising centrally therefrom and having laterally projecting flanges and a connecting web, along the front side thereof and between said flanges, a desk secured to said flanges, a seat support comprising a clamp embracing the edges of said flanges and adjustably mounted on said standard, the flanged portion of said standard being cut away at one point sufficient to permit said seat support to be removed without disturbing said desk, said seat support having portions embracing said web and other portions engaging said flanges, and means for clamping said support in place.

3. A seat construction, comprising a base, a standard rising centrally therefrom and having laterally projecting flanges and an intermediate longitudinal web, a seat support provided with jaws embracing said flanges and web, and a bolt for clamping said jaws against said flanges and web.

4. In a combined desk and seat construc-

tion, a single standard having side flanges affording substantial lateral rigidity, a base, a web member connecting the front of the standard to said base and extending approximately to the top of the standard, a web connecting the rear of the standard to the base, a seat, means for adjustably clamping said seat to the side flanges of said standard and to the web in front thereof, a desk, and means for adjustably clamping said desk to the side flanges of said standard at the upper end thereof.

5. In a construction of the character described, a standard having side flanges extending laterally therefrom, a base, a web connecting the front of said standard to said base and having a slot therein, an annular seat support having yielding portions embracing the side flanges and the web of said standard, and a bolt extending through said yielding portions and through said web for adjustably clamping said seat support to said standard, the base of said standard extending to the front and to the rear of said side flanges.

6. In a combined seat and desk construction, a rearwardly inclined standard having substantial lateral flanges, a base united thereto, a substantial web connecting the front of said base with the front of said standard and extending approximately to the upper end thereof, a web connecting the rear of said standard with the rear of said base, a desk secured to the upper end of said standard and adjustable angularly at approximately the same inclination as said standard, and a seat secured to the side flanges and the front web of said standard and adjustable with relation thereto independently of said desk.

PALMER J. JONES.
